UNITED STATES PATENT OFFICE.

JOSEPH BERG, OF LITTLE ROCK, ARKANSAS.

GAS-ENGINE STARTER.

1,315,274.

Specification of Letters Patent.

Patented Sept. 9, 1919.

Application filed April 14, 1919. Serial No. 289,805.

To all whom it may concern:

Be it known that I, JOSEPH BERG, a citizen of the United States, and resident of Little Rock, in the county of Pulaski and 5 State of Arkansas, have invented certain new and useful Improvements in Gas-Engine Starters, of which the following is a specification.

This invention relates to devices for manually starting gas engines, and has for its 10 object to provide improved means for safeguarding the operator in case of back firing.

It is the aim of this invention to make the automatic releasing mechanism as compact as possible and to protect it from dust and tampering, as well as insure its reliable 15 operation.

Another object is to provide improved and simplified means for locking the starter 20 so that it can not be used to turn over the engine by unauthorized persons.

Other objects will appear as the description proceeds.

The invention will first be hereinafter 25 described in connection with the accompanying drawings, which constitute part of this specification, and then more specifically defined in the claims at the end of the description.

30 In the accompanying drawings, wherein similar reference characters are used to designate corresponding parts throughout the several views—

Figure 1 is a sectional view of the starting mechanism shown applied to the end of 35 an engine shaft, the parts being in position for starting said shaft.

Fig. 2 is a section on the line 2—2 of Fig. 1, showing the slotted arm on the casing to 40 prevent rotation thereof.

Fig. 3 is a sectional view of the starting mechanism similar to Fig. 1, except that the parts are shown in disengaged position, and the engine shaft and part of the starting 45 shaft are omitted.

Fig. 4 is a section on the line 4—4 of Fig. 3.

Fig. 5 is a section on the same line looking 50 in the opposite direction as indicated by the arrows 5—5; and

Fig. 6 is an elevation of the starting mechanism in the same position as in Fig. 2, the casing being shown in section.

In Fig. 1 the end portion of an engine 55 shaft is indicated at 7 as having the usual

radially projecting lug 8 to be engaged by the inclined teeth 9 on the cap portion 10 of the starting shaft 11, which is journaled in the frame member 12. The starting shaft normally is moved axially away from the 60 engine shaft in the usual manner so as to disengage the teeth 9 from the lug 8, and permit said engine shaft to run free from the starting shaft. The parts are in the 65 positions shown in Fig. 1 only when pressure is being exerted on the crank 14 to hold the starting shaft coupled up with the engine shaft, as when starting the engine.

The automatic releasing mechanism includes a pair of disks 15 and 16, and a ring member 17, all of which are housed in a casing 18 which is mounted loosely around the starting shaft 11 and has an arm 19 extending along the frame member 12, as shown in Fig. 2. The outer end portion of 70 said arm 19 is slotted at 20 to loosely engage over a projecting lug 21, which projects far enough from said frame member to permit the casing to be moved with the starting shaft without disengaging the arm 75 from said lug.

The disk 15 is keyed fast on the starting shaft, as at 22, but the disk 16 is loose on 80 said shaft. The facing surfaces of said disks have annular series of ratchet teeth 23 and 24, respectively, which are adapted to be operatively engaged with one another when the parts are in position for starting the engine, as shown in Fig. 1. The disk 16 has an integral sleeve 25 extending along the 85 shaft 11, for some distance beyond the casing 18, and over said projecting portion of the sleeve the hub 26 of the crank 14 is secured in any suitable manner, as by the cross pin 27. The extremity of the starting shaft 90 11 is threaded at 28 to receive a nut 29 which fits loosely in the sleeve 25, and between said nut and the disk 16 there is arranged a spring 30 which is housed in the 95 sleeve and normally holds said disk with its ratchet teeth in engagement with the teeth 23 on the disk 15. The disk 16 may be drawn away from the disk 15, however, by pulling 100 on the crank as shown in Figs. 3 and 6, and may be secured in that position by projecting the bolt 31 of a suitable lock 32, carried by the hub 26 of the crank, in the way of the nut 29, as indicated in dotted lines in Fig. 3. When locked in this way, the disk 105 16 can not be pushed into position to make 110

Fig. 4 is a section on the line 4—4 of Fig. 3.

Fig. 5 is a section on the same line looking in the opposite direction as indicated by the arrows 5—5; and

Fig. 6 is an elevation of the starting mechanism in the same position as in Fig. 2, the casing being shown in section.

In Fig. 1 the end portion of an engine shaft is indicated at 7 as having the usual

its ratchet teeth engage those on the disk 15, and consequently the crank cannot be used to start the engine.

Mounted loosely around the disk 15 and 5 extending also over the disk 16, when the latter is in engagement with said disk 15, is the ring member 17, having a peripheral series of ratchet teeth 34 engaged by a spring 10 pressed pawl 35, Fig. 4, which is carried by the casing 18, preferably in an offset portion 36 thereof. The edge of the disk 16 is stepped annularly at 37 and the vertical face of said stepped portion has a plurality, preferably two, V-shaped teeth 38 adapted to 15 fit in corresponding V-shaped cavities or notches 39 in the adjacent face of the ring member 17. These V-shaped teeth must be engaged with their notches 39 in the ring member in order to bring the ratchet teeth 20 24 on the disk 16 into mesh with the ratchet teeth 23 on the disk 15.

When the starting mechanism is to be used for turning the engine shaft 7, pressure is exerted on the crank 14 to move the starting shaft 11 into the position shown in Fig. 1 25 whereupon the crank is turned in the proper direction, and the crank being connected by the cross pin 27 to the sleeve 25 of the disk 16, will rotate said disk which in turn will 30 rotate the disk 15 on account of their ratchet teeth being in mesh, and thus rotate the starting shaft 11 which is keyed at 22 to said disk 15. Inasmuch as the starting shaft has 35 its inclined teeth 9 in engagement with the lug 8, on the engine shaft 7, the rotary movement of the starting shaft will be transmitted to said engine shaft. When the engine has been started and the shaft 7 begins 40 to turn faster than the starting shaft 11, the ratchet teeth 23 on the disk 15 will slip past the ratchet teeth 24 on the disk 16, the latter disk being moved outward along the shaft 11 against the action of the spring 30. In case of back firing and the consequent 45 rotation of the engine shaft in the opposite direction from that in which the starting shaft is being turned by the crank, the ring member 17 is held against such retrogressive movement by the pawl 35, so that a slight 50 reverse movement of the crank and disk 16 carried thereby will throw the V-shaped teeth 38 on said disk out of the notches 39 in said ring member and thus automatically disengage the ratchet teeth 24 on the disk 16 55 from the ratchet teeth 23 on the disk 15, as shown in Figs. 3 and 6, before injury can be done to the operator. If the retrogressive movement of the engine shaft continues, the V-shaped teeth will ride smoothly along the 60 edge of the ring member between the notches 39.

Having thus fully described my invention, what I claim as new and desire to secure by Letters Patent of the United States, is—

1. In an engine starter, the combination

with a starting shaft, of a disk fast thereon and having an annular series of ratchet teeth on one face, a second disk loose on the shaft and having an annular series of teeth to operatively engage the teeth on the first disk, 70 a ring member mounted loosely around the first disk and having inclined notches in one face, there being inclined teeth on the second disk to engage said notches in the ring member when the ratchet teeth on said second disk are in mesh with the ratchet teeth on the first disk, a crank connected to the second disk, and means for limiting the rotation of the ring member to one direction. 75

2. In an engine starter, the combination with a starting shaft, of a disk fast thereon and having an annular series of ratchet teeth on one face, a second disk loose on the shaft and having an annular series of ratchet teeth to operatively engage the teeth on the first disk, 80 a ring member mounted loosely around the first disk and having inclined notches in one face, there being inclined teeth on the second disk to engage said notches in the ring member when the ratchet teeth on said second disk are in mesh with the ratchet teeth on the first disk, means for limiting the rotation of the ring member to one direction, a crank connected to the second disk, and means for yieldingly holding 85 the second disk with its teeth in mesh with the teeth on the first disk, and notches in the ring member. 90

3. In an engine starter, the combination with a starting shaft, of a disk fast thereon and having an annular series of ratchet teeth on one face, a second disk loose on the shaft and having an annular series of ratchet teeth to operatively engage the teeth on the first disk, a ring member mounted 100 loosely around the first disk and having inclined notches in one face, there being inclined teeth on the second disk to engage said notches in the ring member when the ratchet teeth on said second disk are in mesh with the ratchet teeth on the first disk, means for limiting the rotation of the ring member to one direction, a sleeve on said second disk, a crank connected to said sleeve, 105 an abutment on the shaft within said sleeve and a spring interposed between said abutment and the second disk for yieldingly holding said disk with its teeth in mesh with the teeth on the first disk and notches in the ring member. 110

4. In an engine starter, the combination with a starting shaft, of a disk fast thereon, and having an annular series of ratchet teeth on one face, a second disk loose on the shaft and having an annular series of ratchet teeth to operatively engage the teeth on the first disk, a ring member mounted loosely around the first disk and having inclined notches in one face, there being inclined teeth on the second disk to engage said 125 teeth. 120

- notches in the ring member when the ratchet teeth on said second disk are in mesh with the ratchet teeth on the first disk, means for limiting the rotation of the ring member to one direction, a sleeve on said second disk, a crank connected to said sleeve, an abutment on the shaft within said sleeve and a spring interposed between said abutment and the second disk for yieldingly holding said disk with its teeth in mesh with the teeth on the first disk and notches in the ring member, and a lock carried by the crank and adapted to have its bolt projected through said sleeve into the path of the abutment on the shaft for retaining the second disk away from the first disk and ring member.
5. In an engine starter the combination with a starting shaft, of a disk fast thereon and having an annular series of ratchet teeth on one face, a second disk loose on the shaft and having an annular series of ratchet teeth to operatively engage the teeth on the first disk, a ring member mounted loosely around the first disk and having inclined notches in one face, there being inclined teeth on the second disk to engage said notches in the ring member when the ratchet teeth on said second disk are in mesh with the ratchet teeth on the first disk, a crank connected to the second disk, a casing housing the disks and ring member and movable with the shaft, means for preventing the rotation of said casing, a pawl carried by the casing, and an annular series of ratchet teeth on the ring member engaged by said pawl for limiting the rotation of said ring member to one direction.
6. In an engine starter, the combination with an axially movable starting shaft, of automatic release gearing on said shaft, means for actuating the starting shaft through said gearing, a casing housing said gearing and movable with the shaft, a slotted arm on said housing, and a fixed lug engaging the slot in the arm for preventing the rotation of the casing without disengagement of the lug and arm.
7. In an engine starter, the combination with an axially movable starting shaft, of a disk fast thereon and having an annular series of ratchet teeth on one face, a second disk loose on the shaft and having an annular series of teeth to operatively engage the teeth on the first disk, a ring member mounted loosely around the first disk and having inclined notches in one face, there being inclined teeth on the second disk to engage said notches in the ring member when the ratchet teeth on said second disk are in mesh with the ratchet teeth on the first disk, a crank connected to the second disk, a casing housing the disks and ring member and movable with the shaft, means for preventing the rotation of said casing, a pawl carried by the casing, and an annular series of ratchet teeth on the ring member engaged by said pawl for limiting the rotation of said ring member to one direction.
8. In an engine starter, the combination with a starting shaft, of a disk fast thereon and having an annular series of ratchet teeth on one face, a second disk loose on the shaft and having an annular series of ratchet teeth to operatively engage the teeth on the first disk, a ring member mounted loosely around the first disk and having inclined notches in one face, there being inclined teeth on the second disk to engage said notches in the ring member when the ratchet teeth on said second disk are in mesh with the ratchet teeth on the first disk, a crank connected to the second disk, a casing housing the disks and ring member, means for preventing the rotation of said casing, a pawl carried by the casing, and an annular series of ratchet teeth on the ring member engaged by said pawl for limiting the rotation of said ring member to one direction.

JOSEPH BERG.
